DISPLAY DEVICE

Charles Roberts, New York, N. Y., assignor to
 Multiposter Advertising Corporation, New York,
 N. Y., a corporation of New York

Application May 28, 1938, Serial No. 210,554

16 Claims. (Cl. 40—36)

This invention relates to a moving display mechanism in which an oscillating mechanical movement directly driven by a motor operates transversely a constantly vertical bar clamp which 5 engages each frame holding a display sheet sequentially, and moves the frame a predetermined distance along a closed track circuit in which the frames are free to move.

A duplex bar clamp is shown and is positioned 10 on the oscillating mechanism which is illustrated as a parallel bar movement.

The bar clamp is free to move up and down on each clamp as it traverses its oscillating arc of movement but the clamp itself is always parallel to the long axis of the frame as it is moved along the restraining track circuit.

It has been found that moving displays operating continuously day in and day out are subjected to a very severe service, one of the objects of this invention is to eliminate chains and similar structure which stretch and change the essential coordination of the machine's mechanism. A mechanism as herewith disclosed cannot become deranged by wear if properly designed 25 to that extent to cause the stoppage of the machine. Another valued feature which gives assured operation is the mechanical locking gate which controls the first two frames in the magazine or the two frames that are about to be moved, 30 one into display position and the other out of display position, along the circuit by the oscillating mechanism.

Another object is to devise a double clamp which engages each frame as it is carried forward along 35 the track circuit such that although the two clamps engaging the frame are free to travel up and down on the frame as dictated by the arc generated by the oscillating movement yet the frame in transit will be firmly held against any 40 forces which might free it from the clamps either in a forward or backward direction until the frame has completed its predetermined transit. Another object is to push the compacted frames forming the magazine in two mechanical steps 45 at succeeding intervals, one portion of the frames first and the rest of the frames at the end of the display pull-away to reduce to a minimum any peak load on the motor operating the device; this procedure is most practical to relieve the motor's 50 operation. Other objects and details will be more explicitly developed in the ensuing specifications and accompanying drawings which are to be considered as illustrative only of the theme of my invention.

Fig. 1 is a front elevation partially in section of

my display machine, showing the placement of the motor operating the device in dotted outline in the base thereof.

Fig. 2 is a side elevation of Fig. 1 the base being partially broken away to show the reduced speed power output shaft 20 of the motor 5.

Fig. 3 is a sectional elevation of the machine taken on line 3—3, Fig. 2, the motor 5 being omitted for clarity. A section of the central panel being cut through to show the frames compacted behind the same.

Fig. 4 is a sectional elevation of the machine taken on lines 4—4 of Fig. 5. Fig. 4 also shows clearly when compared with Fig. 3 the amplitude of the oscillating parallelogram movement at its 15 two extreme positions and the relationship of the mechanical frame lock at one end of the magazine and the release mechanism and forced movement of those frames in the magazine which in the cycle have not yet been moved forward, a 20 frame width, by the mechanical actuated frame pusher.

Fig. 5 is a vertical section taken as line 5—5, in Fig. 4.

Fig. 6 is a schematic plan view of the magazine 25 and the two extreme positions of the oscillating duplex clamp which actually transports each frame along the empty portion of the track circuit of the machine.

Fig. 7 is the same as Fig. 6 only it shows the 30 duplex clamp in full lines at a mid position in its oscillating movement and at a coincident moment the mechanically actuated frame pusher having completed its movement forward of a majority of the frames in the magazine in order 35 to reduce the peak load on the motor, in contrast, if the duplex clamp shown in dotted lines was required to move forward the entire number of frames compacted in the magazine, one frame width, to effect proper registration.

Fig. 8 is an enlarged section taken on line 8—8 in Fig. 4 to show an automatic pawl 30 interposed at a point in the compacted magazine where the mechanically actuated pusher, see Fig. 9, moves forward a portion of the compacted frames to divide the motor peak load. The pawl 30 restrains the frames so moved to prevent displacement which might otherwise stall the motor.

Fig. 9 is an enlarged section taken on line 9—9 50 in Fig. 4 and shows clearly the amount of movement of the frames moved forward in the magazine to minimize the peak motor load.

Fig. 10 is an enlarged sectional elevation to show the coordination of the mechanical lock 55

with the three adjacent frames, A, B, and C as shown in Fig. 3.

Fig. 11 shows the relative position of the frames and lock as frame A is moved away by the oscillating arm with the lock in a raised and unlock-
ing position in respect to frame A.

Fig. 12 shows the frame lock again lowered and in a locking position in respect to frame B.

Referring to the drawings for a more detailed description of the invention, reference being had more particularly to Fig. 1 of the drawings, number 1 indicates the glass display window, 2 is the cabinet of the machine, 3 are lighting cowls for the display; number 4 a lock detaining the rear panel which has hinges 6, see Fig. 2, and 5 is the motor in the base of the cabinet to operate the machine. Referring to Fig. 3, number 7 indicates the frames or holders into which the display sheets are secured and which are slideably retained on upper and lower tracks 8, which form a closed circuit. Frames 7 are normally compacted to form a magazine along a portion of the track 8, see Figs. 5 and 6. Two parallel bars 9 and 10, see Figs. 3 and 4, are fulcrumed on lower fixed bearings, 11 and 12 respectively, the upper extremities of the bars 9 and 10 are likewise fulcrumed into a T-shaped cross head 13, see Figs. 3 and 4, by bearings 14 and 15 respectively making in effect a closed parallelogram movement, the cross head 13 always remaining in a vertical position during its transit from the position shown in Fig. 3 to the position shown in Fig. 4. On the cross head 13 is secured by means of two hinges 16 and 17, see Figs. 3, 4, and 5, the swing member or pusher 18, as well as the swing lock 19, the bar 80 ties the top and bottom arms, which compose the swing lock 19, rigidly together. Looking at Fig. 5 and at the phantom drawing of the elements 16, 18, and 19 at the left end of the drawing showing these elements at the extreme left position, at which point they pick up frame A, it is readily seen that the element 18 under influence of torsion spring 21, see Fig. 3, which keeps the extremity of the pusher 18, recessed in 45 to the bottom of the U-shaped frame A while the lip 22 of swing lock 19, also under influence of spring 21, bears against the forward edge of the U-formed frame and forms a lock to prevent the frame A from falling ahead of the oscillating arm 50 while in transit to the right extreme position shown in full lines in Fig. 5. By virtue of the reversal of movement of the assembly 16, 18, and 19 at their position at the extreme right position in Fig. 5 the edge 24 of frame E forces the pusher element 18 to recede inwardly and coincidentally it is noted that the cam arm 25 see Fig. 3, secured to the main vertical panel 27 of the machine has contacted with the upwardly extended arm 26 attached to bar 80 as the oscillating mechanism 60 has swung into position as illustrated in Fig. 3, thus the lip 22 has been positively forced away from locking contact with the U-shaped frame E and as the oscillating mechanism reverses its motion the frame in question is completely unlocked and is positively retained in the position as shown in Fig. 3 by the retaining action of the spring actuated pawls 28 and 29, see Fig. 5. Turning now to Fig. 4 wherein the oscillating arms 9 and 10 are at their opposite extreme positions due 65 to the angle of its contact with the edge of frame A, see Fig. 5, it is depressed and slides into position as seen in dotted lines at the left of Fig. 5 so that a reversal of movement of the oscillating arms 9 and 10 the frame A is carried with the members 18 and 19 providing the arm 30, see

Fig. 5, is in an unlocked position. It has been found that it is very essential for perfect functioning of a machine of this character that the leading two frames in the compacted magazine always register at a precise point ready to synchronize with the transition element. If these two frames become deranged during shipping from the factory or from one point to another, the machine locks up due to the misalignment of these two frames. I have devised a duplex frame lock, that is, it is duplex in that it positively controls these two leading frames in the magazine. To clearly show this action, Fig. 10 shows the two leading frames in the magazine respectively A, and B with C the succeeding frame; 31 is the locking arm which may be integral with or rigidly attached to the locking gate slide bar 32.

Slide bar 32, see Figs. 3 and 4, is retained by pins 33 which act as crossheads moving in slots 34. On arm 35 secured to slide bar 32 is attached spring 36 which is secured under slight tension to the chassis or panel 27 at 36a so that normally element 32 is retained in the lowered position as seen in Fig. 3. A cam lever 39, see Fig. 4, fulcrumed on panel 27 at 40 is connected to slide bar 32 by virtue of the pin 37 secured to bar 32 which slides in slot 38 cut in cam lever 39. A pin 42 on parallel bar 19 is so positioned that it contacts with the cam surface 41 on lever 39 just before the oscillating elements have arrived at the position 30 as is shown in Fig. 4, the contact of pin 42 with cam surface 41 elevates the locking slide bar 32 with its frame locking arm 31. This movement is specifically shown in its relationship with frames A, B, and C in, first, Fig. 10 wherein frame 35 A is locked due to locking bar 31 contacting the U shaped side wall of frame A whereas when slide bar 32 is elevated by the above described action the bar 31 is then shown in its elevated position in Fig. 11 now having registered with 40 aperture 51 in frame A and frame A has started to move away. As slide bar 32 again is lowered, due to spring 36, and also as an additional safeguard by pin 42, contacting with cam surface 41a on lever 39 positively lowering bar 32, lock- 45 bar 31 has again been lowered and has passed through opening 38 in frame B, allowing frame B to reach a registering position in the circuit as shown in Fig. 11, as and when during the oscillating mechanism transit to the left as seen in 50 Fig. 3 the following described mechanical pusher mechanism has forced forward all frames in the compacted magazine from the point Z, see Fig. 7, to frame A therein. This movement which is chosen at this approximate point Z is essentially 55 chosen to reduce very materially the peak load on the motor and is accomplished as follows: looking at Fig. 4, roller pin 46 secured to oscillating element 10 contacts in its arc of travel with the lever 44 at its extremity 45, which lever 46 is 60 fulcrumed at 43 and which has a slot 48 cut into its upper extremity. A pin 49 secured to the roughly T shaped arm 50 which in turn is cross headed by pins 53 and 54 secured to the panel 27 and which are slideable in the slots 51 and 52. 65 In this manner as and when lever 44 is turned on fulcrum 43 the pin 49 engages the slot 48 and draws member 50 to the left, see Fig. 4. Pawls 70 and 71 which engage the back side of frames 7 through the cut outs 84 and 85 respectively, see Fig. 4, also Fig. 9, are secured at the upper and lower extremities of element 50 by the pivot rod 77 which in turn is secured to element 50 by the clamps 78 and 79. Thus the pawls 70 and 71 engage the proper frame 7 and 75

force it and all of the preceding frames with their respective displays forward one frame width as is graphically shown in Fig. 7 at Z. The spring 58 causes the above frame forcing assembly to return to its initial position, the pawls over-riding the next succeeding frame as it in turn is pushed forward to fill up gap Z by the final movement of the remainder of the frames 7 as will be shortly described. As the oscillating movement, see Fig. 10 3, completes its movement to the right as shown and carrying a particular frame 90 in its transit, which frame 90, still securely held by pusher pawl 18, contacts frame 91 and pushes it forward and hence forces all the remaining frames forward, 15 thereby dividing the magazine resistance into two distinct and succeeding movements, the first, produced by cross head element 59 and having completed its movement, dividing the magazine before the last movement begins; in this manner the 20 motor load is reduced in contrast as if all the frames but one, for registration purposes, were moved at one time by the motor. Transverse springs 68 and 69 are positioned across the top and bottom of the unfilled portion of the circuit 25 to prevent the displays from falling inward across the path of a succeeding display movement.

The operation of the machine is clearly understood to those skilled in the art from the above description, the oscillating assembly preferably 30 a parallelogram actuated by the motor engages the displays, at one extremity of its movement by virtue of the pivoted elements 18 and 22 which always remain aligned to the display or frame in question while in transit, the elements 18 and 22 35 being free to slide up and down on the frames 7 as they follow the arc of the oscillating movement. As the oscillating movement moves to the left it relocks frame B, see Fig. 11, and moves the compacted frames in the magazine forward the 40 width of one frame 7, in two distinct and succeeding steps, the locking element 22 being withdrawn from the frame at the conclusion of its transit due to the action of cam 25 and the pushing element 18 ceases to function as the oscillating assembly reverses itself at the extremity of 45 its movement. The pawls 28 and 29 retain the frame, just carried forward, in contact with the next compacted frame in the magazine.

It should be noted that if the load (motor 50 torque) card is studied of this type of display machine, there is seen to be a very sharp "peak load" at the one point in its cycle where the displays compacted in the magazine are all advanced together along the circuit, a step essential to registration with the window. This movement calls for a motor of unneeded size, cost, and weight for the operation of the rest of the cycle which 55 consists of moving a single display across the show window. Therefore, my invention embraces means to very materially reduce this "peak load" by spreading it in two or more sequential movements of the magazine and is a valuable contribution. It should also be observed 60 that this procedure is essentially different from advancing one or two displays in the magazine for proper registration as such a step does not reduce the peak load and accomplish the desired result.

70 What I claim and desire to secure by United States Letters Patent is:

1. In a display device containing a show window and comprising a plurality of overlapping displays movably restrained in a closed circuit, 75 said displays compacted in a portion of said cir-

cuit, a motor driven oscillating mechanism, latching means on said oscillating mechanism, means to maintain said latching means parallel with the edge of said displays movably restrained in said circuit, means to lock said displays when compacted in a portion of said circuit including that portion opposite said window and synchronizing means to unlock said display locking means as and when said oscillating mechanism is at one of its extreme oscillating positions. 10

2. In a display device containing a show window and comprising a plurality of overlapping displays movably restrained in a closed circuit, means to compact said displays along that portion of said circuit that traverses said window, 15 oscillating motor driven means to move one display at a time along that portion of said circuit empty of said compacted displays and means associated with said oscillating means during one normal throw of its oscillation to advance a majority of said compacted displays along said circuit a predetermined distance thereof and means just at the termination of said normal oscillation to move the remaining displays. 20

3. In a display device containing a show window and comprising a plurality of overlapping displays movably restrained in a closed circuit, means to compact said displays along that portion of said circuit that traverses said window, 30 oscillating motor driven means to move one display at a time along that portion of said circuit empty of said compacted displays and means associated with said oscillating means during one normal throw of its oscillation to advance a portion of said compacted displays along said circuit a predetermined distance thereof and means just at the termination of said normal oscillation to advance the remaining displays. 35

4. In a display device containing a show window and comprising a plurality of overlapping compacted displays, movably restrained in and partially filling a closed circuit therefor, motor driven means to move said displays one at a time along an empty portion of said circuit; said means consisting of an oscillating parallelogram, 45 the lower end of which is fulcrumed at a point below the horizontal plane of said window.

5. In a display device containing a show window and comprising a plurality of overlapping compacted displays, movably restrained in and partially filling a closed circuit therefor, motor driven means to move said displays one at a time along an empty portion of said circuit; said means consisting of an oscillating parallelogram, the lower end of which is fulcrumed at a point below the horizontal plane of said window, and display latching means on the upper end of said parallelogram. 55

6. In a display device containing a show window and comprising a plurality of overlapping compacted displays, movably restrained in and partially filling a closed circuit therefor, motor driven means to move said displays along an empty portion of said circuit; said means consisting of an oscillating parallelogram, the lower end of which is fulcrumed at a point below the horizontal plane of said window, and latching means on the upper end of said parallelogram, and cooperating means on said displays to engage said latching means. 60

7. In a display device containing a show window, a chassis, said chassis containing a plurality of overlapping compacted displays movably restrained in and partially filling a closed circuit supported by said chassis; a motor driven oscil- 75

- lating parallelogram movement, the upper cross member of said parallelogram supporting latching means to connect with said displays to move said displays along the empty portion of said circuit. 5
8. In a display device containing a show window, a chassis, said chassis containing a plurality of overlapping compacted displays movably restrained in and partially filling a closed circuit 10 supported by said chassis; a motor driven oscillating parallelogram movement, the upper cross member of said parallelogram supporting latching means to connect with said displays to move said displays along the empty portion of said circuit, and means to fulcrum the vertical parallel members of said parallelogram to the chassis of said display device. 15
9. In a display device containing a show window, a supporting chassis, said chassis containing a plurality of overlapping compacted displays movably restrained in and partially filling a closed circuit, a motor driven oscillating parallelogram, the minor cross member at one end of said parallelogram supporting latching means 20 to connect with said displays to move said displays along the empty portion of said circuit, and means to fulcrum the other ends of the major parallel members of said parallelogram to said chassis. 25
10. In a display device containing a show window, a supporting chassis, said chassis containing a plurality of overlapping compacted displays movably restrained in and partially filling a closed circuit supported by said chassis; a motor, 30 a closed parallelogram movement formed by two comparatively long sided elements and two comparatively short sided elements, one of the short elements formed by said chassis and fulcrumed thereto, the other short element supporting engaging means to move said displays one at a time and means to oscillate said parallelogram by said motor. 35
11. In a display device containing a show window, a chassis, and comprising a plurality of overlapping displays movably restrained in a closed circuit secured to said chassis, means to compact said displays along that portion of said circuit traversing said window, motor driven means to transfer one display at a time along 40 the empty portion of said circuit, and means synchronizing with said motor driven means to advance along said circuit a predetermined distance, said compacted displays in a plurality of groups seriatum during each interval consumed 45 to transfer one display at a time along said empty portion of said circuit. 50
12. In a display device containing a show window, a chassis, said chassis containing a plurality of overlapping compacted displays movably restrained in and partially filling a closed circuit 55
- supported by said chassis; a motor, a closed parallelogram movement formed by two comparatively long sided elements and one comparatively short sided member, the other short side of the parallelogram formed by the two long sided elements, each terminating into a fulcrum and spaced apart, and secured to said chassis and means to oscillate said parallelogram by said motor. 5
13. In a display device containing a show window and comprising a plurality of overlapping displays movably restrained in a closed circuit, means to compact said displays along that portion of said circuit that traverses said window, oscillating motor driven means to move one display at a time along that portion of said circuit empty of said compacted displays and means associated with said oscillating means during one normal throw of its oscillation to advance a portion of said compacted displays along said circuit a predetermined distance thereof and means just at the termination of said normal oscillation to move the remaining displays the same distance. 10 15
14. In a display device containing a show window and comprising a plurality of overlapping compacted displays, movably restrained in and partially filling a closed circuit therefor, motor driven means to move said displays one at a time along the empty portion of said circuit, 20 said means consisting of an oscillating parallelogram, one end of which is fulcrumed at a point beyond the plane encompassed by said window and display latching means on the other end of said parallelogram. 25 30 35
15. In a display device containing a show window and comprising a plurality of overlapping compacted displays, movably restrained in and partially filling a closed circuit therefor, motor driven oscillating means to move said displays one at a time along the empty portion of said circuit, 40 said oscillating means fulcrumed at one extremity at a point beyond the plane encompassed by said window and display latching means engageable along the leading edge of said displays at the other extremity. 45
16. In a display device containing a show window, a chassis, said chassis containing a plurality of overlapping displays, movably restrained in and partially filling a closed circuit therefor, motor driven oscillating means to move said displays one at a time along the empty portion of said circuit, 50 said oscillating means fulcrumed at one end to said chassis and display latching means at its other extremity and compensating means to maintain said latching means parallel with the display as it is moved along the empty portion of said circuit. 55

CHAS. ROBERTS. 60
